DENTAL DAM

Roberto Vazquez Arroyo, Pasaje Continental 14, Ciudad Juarez, Chihuahua, Mexico
Filed Feb. 1, 1963, Ser. No. 255,469
4 Claims. (Cl. 32—35)

This invention relates to a dental appliance and more particularly to an appliance to be positioned in the mouth of a patient to facilitate the work of a dentist on the patient's teeth.

A primary object of the invention is the provision of a device of this character comprised of a pair of longitudinally curved channels connected at one end by a bridge, the channels being adapted to contain pieces of cotton, which are customarily cut in the form of relatively short cylindrical members, for the purpose of absorbing saliva, and at the same time spacing the lower lip away from the gum and the teeth to be treated.

An additional object of the invention is the provision of such a device provided with an outer channel which is adapted to be positioned between the teeth and the lip interiorly of the mouth, and a second channel adapted to be positioned inside the mouth behind the teeth, each channel containing a piece of absorbent cotton, and the channels being connected at one end by a bridge to which is attached a tongue guard or deflector, which prevents the tongue from contacting and moistening the teeth being treated.

A further and more specific object of the invention is the provision of a device of this character which may be made arcuate or concave to either the right or the left, so as to fit either side of the patient's mouth, and wherein the bridge positioned at the center, serves additionally to prevent complete closure of the mouth.

A further and more specific object of the invention is the provision of such a device having a light in the bridge so as to illuminate the teeth being treated.

Still other objects reside in the combinations of elements, arrangements of parts, and features of construction.

Other objects will in part be obvious and in part be pointed out as the description of the invention proceeds and shown in the accompanying drawing wherein there are shown preferred embodiments of this inventive concept.

In the drawing:

FIGURE 1 is an end elevational view of one form of appliance constructed in accordance with this invention, in positioning over the teeth of a patient, the latter being indicated in dotted lines.

FIGURE 2 is a side elevational view of the device of FIGURE 1 as viewed from the interior side or the side normally positioned within the mouth, cotton cylindrical members being shown dotted.

FIGURE 3 is a top plan view of the construction of FIGURES 1 and 2.

FIGURE 4 is a sectional view taken substantially along the line 4—4 of FIGURE 3 as viewed in the direction indicated by the arrows.

FIGURE 5 is a top plan view of a modified form of construction incorporating a light in the bridge piece, the construction of FIGURE 5 being adapted for the left hand side of the mouth, in contrast to that of FIGURE 3 or opposite thereto; and

FIGURE 6 is a side elevational view of an article or appliance similar to that of FIGURE 5, but constructed to fit in the right side of the mouth.

Similar reference characters refer to similar parts throughout the several views of the drawing.

Having reference now to the drawings in detail, and more particularly to FIGURES 1 to 4, one form of device constructed in accordance with the instant invention is

2

generally indicated at 10, and is of plate like material comprised of an outer channel member 11, an inner channel member 12, a bridge 13 connecting the channel members, and a tongue guard or deflector 14.

5 The device 10 is preferably comprised of resilient compressible material, such as rubber, to conform readily to the patient's mouth and provide a minimum of discomfort.

The outer channel member 11 is arcuate longitudinally or in plan view, as best shown in FIGURE 3, and also arcuate transversely as best seen in elevation in FIGURE 1. Channel member 11 is adapted to fit snugly between the gums G supporting the lower teeth T and the lower lip L, and has positioned therein a cotton pellet C which is adapted to absorb saliva, the pellet being of the type normally employed by dentists in such position and for a similar purpose, but the pellet itself rather than the channel normally serving to space the lip from the gum. Inner channel 12 is similarly arcuate, conforming in configuration to channel 11 both transversely and longitudinally, but is slightly shorter in extent, and is adapted to contain a similar cotton pellet C for the purpose of absorbing moisture interiorly of the mouth. In conventional practice, such an interior pellet cannot be used, since there is nothing normally to hold it in position.

20 Bridge 13 is, as best shown in FIGURES 1 and 4, relatively thick, and serves as a support to prevent the upper teeth closing on the lower teeth during work thereon.

Extending from the top of bridge 13 in a smooth integral curve to the outer edge of inner channel member 12 the tongue guard or deflector 14 overlies the end of the inner cotton pellet, and serves to prevent the tongue T' from contacting the teeth which are being treated. As is well known, under certain circumstances, moisture precludes proper treatment of teeth, and such moisture is imparted 30 to the teeth as the tongue comes in contact with them. Additionally, the tongue may impede the dentist's work, and it is, therefore, desirable that it be maintained out of the way with the least possible discomfort to the patient.

By virtue of the arrangement described, the dentist is 35 free to work on the lower teeth on either side of the mouth, in accordance with the construction of the appliance, with cotton saliva absorbing pellets positioned on either side of the teeth and gums being treated, and with the tongue precluded from coming into contact with the teeth upon which the dentist is working.

45 In the illustrative embodiment of the invention shown in FIGURES 1 to 4 an appliance for treating the teeth on the right side of the mouth is shown, the channel members 11 and 12 extending interiorly of the mouth and the bridge 13 being substantially centrally positioned. It will 50 be obvious, however, that by reversing the curvature of the channels 11 and 12 and by positioning the bridge at the opposite end a substantially identical but reversed article may be employed for the left side of the mouth.

55 In FIGURE 5, for example, there is shown a modified form of the invention wherein channels 11a and 12a are curved for the opposite side of the mouth. This modification is substantially identical to that previously shown except that the bridge 13a may be slightly thicker, if desired, and is provided with a recess 16 into which fits a socket 17 for a small light bulb 18. A cord 19 extends out of a suitable opening 20 in the side of the bridge, and extends out of the patient's mouth to any suitable source of electric current, so that the teeth being treated may be adequately illuminated. A similar device is disclosed in FIGURE 6, but in this instance the curvature of the channels is opposite, for treatment of the right hand side of the mouth. This embodiment of the invention discloses a bridge 13b connecting channel members 11b and 12b, with a recess 16b containing a socket 17b for a light 18b, the light 18b being supplied with current by means of a cord 19b extending through an opening 20b in the side of bridge

13b. It is to be noted that the bridge per se extends to the inner side of each of the channel members 11 and 12, and that the tongue guard or deflector 14 extends to the outer side of the inner channel member 11.

The device of the instant invention may be made of any desired material, although a relatively soft, resilient material, such as rubber, or a suitable resilient or deformable plastic may be employed in order to impart maximum comfort to the patient's mouth, as well as facilitate the moving of the appliance within the patient's mouth for the convenience of the dentist.

From the foregoing it will be seen that there is herein provided an improved dental appliance, which accomplishes all the objects of this invention, and others, including many advantages of great practical utility and commercial importance.

As many embodiments may be made of this inventive concept, and as many modifications may be made in the embodiments hereinbefore shown and described, it is to be understood that all matter herein is to be interpreted merely as illustrative, and not in a limiting sense.

I claim:

1. A dental appliance of resilient and deformable plate-like material, for use in the mouth, comprised of a pair of horizontal and spaced apart open top inner and outer longitudinal extending channels, each having an axis which is convex outwardly in plan view to generally correspond to the line of teeth, 25 the vertical transverse cross-section of each channel being U-shaped with vertical top legs and of an overall height approximately equal to the overall width between said legs, each of said channels in use thus being adapted to compressably receive short cylindrical members of cotton for the purpose of absorbing saliva, and the outer cylinder member also spacing the lower cheek away from the gum and the teeth to be treated, 30 the adjacent legs of the channels being so spaced apart as to hug the side face of the gums on each side of a plurality of lower teeth when the appliance is in use, a bridge of inverted U-shape as viewed in vertical cross-section, oriented perpendicularly to the axes of the channels as viewed in plan, and at a front end of each of said channels, the legs of said bridge merging smoothly with the closer pair of legs of said chan- 40

45

nels, the clear height of said bridge above said channels being substantially equal to the overall height of said channels, the width of the bridge in a direction parallel to said channel ends being approximately equal to the overall width of the bridge as seen in vertical cross-section, whereby in use the bridge completely overlies a tooth,

and a tongue guard extending horizontally as seen in vertical cross-section from the full extent of the top of said bridge by a smooth externally convex curve to said innermost vertical leg of the inner channel, and merging smoothly, as seen in longitudinal elevation, from the back of the top of said bridge to a horizontal top of said innermost leg by a smooth curve, whereby the patient's tongue is prevented from contacting and moistening the teeth to be treated, the latter teeth being located adjacent said bridge and between said channel members when the appliance is in use.

2. The structure of claim 1 wherein said outer channel is of greater longitudinal length than said inner channel, and both channels have smoothly rounded rear ends as viewed in plan.
3. The structure of claim 1, wherein the top of said bridge is relatively thicker than the remaining portions of the appliance to thus serve better as a support in preventing the upper teeth from closing on the lower teeth during work thereon.
4. The structure of claim 1, wherein the bridge is provided with horizontal recess means oriented parallel to the channels and midway between the latter as seen in plan, a socketed light bulb within the recess, and a cord for connection to an external source of electricity extending from said light and through the outer leg of said bridge.
